UNITED STATES PATENT OFFICE.

JAMES R. DUNCAN, OF NEW YORK, N. Y.

CLOSURE FOR PLUMBING-TRAPS OR THE LIKE.

SPECIFICATION forming part of Letters Patent No. 784,931, dated March 14, 1905.

Application filed September 27, 1904. Serial No. 226,115.

To all whom it may concern:

Be it known that I, JAMES R. DUNCAN, a citizen of the United States, residing at New York, in the county and State of New York, have invented certain new and useful Improvements in Closures for Plumbing-Traps or the Like, of which the following is a specification, reference being had to the drawings accompanying and forming part of the same.

In modern sanitary plumbing systems it is desirable and in many cases necessary that traps, bends, and the like be so constructed as to offer ready access to their interior for the purpose of inspection, cleaning, &c. Such devices are therefore provided with suitable apertures and removable closures. The latter must fit tightly, so as to withstand the internal pressure of the system, and at the same time should be easily removed when desired. Where the closure and the surface on which it seats are both made of iron, it is found that the two frequently rust together to such an extent as to make the removal of the cap impossible or extremely difficult. It has therefore been proposed to make the closure or cap of brass, which of course does not corrode as iron does, or to make the closure of brass or iron and provide in the aperture a thimble of brass to receive the closure. The latter method is effective for rendering the cap readily removable, but possesses certain disadvantages in construction. For example, before a plumbing system is pronounced ready for use it is subjected to high internal pressure to test its tightness and strength. For this purpose the trap-holes, &c., must be closed. Inasmuch as the brass thimble to be used as the closure-seat cannot withstand tight calking between it and the surrounding iron walls of the opening in which it fits it is customary for testing purposes to calk an iron plug very firmly in the opening. After the test is made the plug is removed and the calking, usually lead, is cut out. This makes the testing a very troublesome procedure and one that necessitates considerable labor after its completion to put the system in final shape by removing the plugs and calking, then fitting and lightly calking in the brass thimbles

or rings which are to receive the removable closure.

I have therefore been led to devise my present invention, which has for its object to provide a closure for such apertures which may be seated and held with sufficient firmness to withstand the necessary tests and yet be removable with the greatest readiness. For this purpose I locate in the inside of the aperture a flaring or tapered ring of brass constituting a seat for the closure, also preferably of brass, which is of corresponding shape. The latter is forced into the seat, thereby forming a perfectly tight joint, by a cap, preferably of brass, which screws over the outside of the walls of the aperture. The screw-threads of the cap and hub or collar on which it is secured are thus completely protected from the moisture in the pipe. As will be readily understood, such a construction furnishes a perfectly tight joint which will withstand any pressure to which it may be subjected, but which can be readily opened for cleaning or inspecting the interior of the pipe by removing the outer cap and lifting out the brass plug.

The invention itself consists in the novel features and combinations of elements herein-after described, and more particularly set forth in the claim.

A convenient embodiment of the same is shown in the accompanying drawings, in which—

Figure 1 is a longitudinal section of a trap to which my invention is applied. Fig. 2 is a perspective view of the closure or plug used in the construction shown in Fig. 1.

The trap illustrated is of the double hand-hole type, having a pair of nipples or collars 1, 2, constituting the hand-holes. The inside of each is screw-threaded, as at 3, and provided with a shoulder, as 4, upon which rests the exteriorly-threaded ring or seat 5. The latter is preferably made of brass and tapers downwardly on the inside, as shown. Closely conforming to the taper of the ring 5 is a closure or plug 6, also preferably made of brass. This member is shown in perspective in Fig. 2. It is provided with a nut or stud

7, which may be engaged by a wrench in order to start the closure from its seat, and has also a bail or other device 8 for easily lifting the closure from its place. The plug 6 would be 5 of such size relative to the seat 5 that it will not rest therein flush with the top of the ring and collar, but will project above the same a slight distance—say a sixteenth, eighth, or quarter of an inch.

10 Over the closure or plug 6 is a cap 10, having interior threads to engage those on the outside of the collar or hub, as shown. The inner side of the top of the cap has a cavity 11 to receive the stud 7 of the plug 6, so that 15 the cap will bear on the plug around the periphery of the latter instead of on its wrench-stud. This plan puts the strain on the parts best adapted to withstand the same—namely, on parts removed from the centers of the cap 20 and closure—thus obviating any tendency to buckle. To provide space for the depression or cap 11, the top of the cap need not be thickened, but may be provided with a boss 12. The latter may be squared or otherwise shaped 25 for ready engagement by a wrench for removing the cap, or the wrench may be applied to the body of the cap in the usual way. As for the material of which the cap is made, I prefer brass, as this metal does not rust, and the 30 cap may therefore be left in place for a long period and still be at all times readily removable.

I have shown my closure applied only to the hand-holes of a trap; but it will be obvious that it may be used wherever an easily-removable closure is desired, such as in sewer-fittings, rain-leaders, and plumbing-fittings of all kinds. Whether the section of pipe in which it is used is connected to the adjoining sections by calking, as would be the case with 35 the trap illustrated in the drawings, or by screw-threads is of course immaterial.

What I claim is—

The combination of a fitting having a hand-hole or similar opening formed in a neck integral with the body of the fitting, said opening having an inner shoulder, a tapered seat of non-corrodible metal screw-threaded in the opening and seated on the shoulder, a correspondingly-tapered closure of similar metal 45 fitting the seat and having a stud or boss to be engaged in removing the closure, and a cap of non-corrodible metal screwed upon the neck over the closure and having an imperforate top with a cavity in its inner surface to receive the boss on the closure, whereby the closure is engaged around its periphery only, and forced firmly into its seat by the pressure of the cap, substantially as shown and described.

JAMES R. DUNCAN.
